COMBINED STAIRWAY POST AND BRACKET

Louis Blum, Pittsburgh, Pa.

Application October 18, 1956, Serial No. 43,398

Term of patent 14 years

(Cl. D13—7)

The essential features of my design reside in the portions shown in full lines.

I claim:

The ornamental design for a combined stairway post and bracket, as shown and described.
